UNITED STATES PATENT OFFICE.

JOSEPH PICURI, OF JERSEY CITY, NEW JERSEY.

BUILDING-COLUMN.

1,190,002.

Specification of Letters Patent.

Patented July 4, 1916.

Application filed May 19, 1915. Serial No. 29,114.

To all whom it may concern:

Be it known that I, JOSEPH PICURI, a citizen of the United States, residing at Jersey City, in the county of Hudson and State of New Jersey, have invented certain new and useful Improvements in Building-COLUMNS; and I do hereby declare the following to be a full, clear, and exact description of the invention, such as will enable others skilled in the art to which it appertains to make and use the same.

This invention relates to columns employed in building constructions, and the primary object of the invention is to provide a building column which is constructed of a steel or analogous metal shell reinforced or filled with concrete, and to provide a novel form of construction for connecting the columns in series for preventing accidental displacement of one column with respect to another.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a vertical section through a building column constructed in accordance with this invention, Fig. 2 is a top plan view of one of the caps of the column, and Fig. 3 is a cross sectional view on the line 3—3 of Fig. 1.

Referring more particularly to the drawings, 1 designates the outer shell of the column, which may be constructed of a steel tube, pipe or similar structure. The tube or shell 1 has a foundation cap 2 positioned beneath its lower end. The foundation cap 2 is provided with an annular boss 3 formed upon its upper edge, the inner surface of which forms a vertical wall, at 4, against which the outer surface of the lower end of the shell 1 rests. The lower end of the shell 1 rests upon a transversely extending shoulder 5 formed within the cap. The cap 2 is hollow, and has a plurality of annular ribs 6 formed thereupon, which are provided for receiving concrete therebetween, for preventing accidental displacement of the cap 2. A transversely extending flange 7 is formed

upon the bottom or lower edge of the cap 2, and is braced by ribs or braces 8, which are secured to the upper surface of the flange 7 and extend upwardly therefrom, as is clearly shown in Fig. 1 of the drawings.

The shell 1 has a cap 10 mounted upon its upper end, which cap includes a sleeve 11, having an annular boss 12 formed upon its lower end, which provides shoulders for engaging the upper end of the shell 1. The sleeve 11 has annular ribs 13 formed therein, which are provided for receiving concrete therebetween and preventing accidental displacement of the cap after the shell has been filled with concrete or a filler of similar nature.

The cap 11 has two transversely extending wings 14 and 15, which are braced by ribs 16. The wings 14 and 15 are provided for supporting the ends of girders which may be employed in the construction of the building wherein the columns are used. An inwardly extending flange 17 is formed within the sleeve 11, and it is provided for reinforcing the cap as well as preventing the accidental displacement of the connecting structure 20.

The connecting structure 20 includes a sleeve or shell 21, which is constructed of any desired kind of metal, and has its lower end flared, as is shown at 22. The sleeve 21 is positioned centrally within the shell 1, and it has a second sleeve 23 positioned centrally therein. The sleeve 23 is held in place by a plurality of bars 24, which are positioned between the outer surface of the sleeve 23 and the inner surface of the sleeve 21. The bars 24 are positioned radially about the central axis of the sleeve, and are held in place by bolts 25, which extend through the sleeve 21, the bars 24, and are screw threadably inserted in the sleeve 23, at spaced intervals along the length of the same.

The shell 1 has a reinforcing sleeve 30 mounted centrally within its lower end, within which sleeve is mounted a sleeve 31, which is of smaller diameter than the sleeve 30. The sleeve 31 is held properly spaced within the sleeve 30 by metallic bars 32, which are held in place and secured to the sleeves 30 and 31, by bolts 33, which extend through the sleeve 30, the blocks 32, and have their inner ends screw threadably seated in the sleeve 31. The sleeves 30 and 31 are positioned at the lower end of the

entitled, provided such alterations are comprehended within the scope of what is claimed.

45

What is claimed is:—

A building column comprising a cap, a shell carried by said cap, reinforcing means secured to the cap and extending upwardly within said shell, a cap carried by the upper 50 end of the shell and provided with a central opening, wings formed on the second mentioned cap, a shell positioned on the second mentioned cap, a cylindrical sleeve extending through the second mentioned cap 55 into both of the shells and provided with its lower end flared, an inner sleeve positioned within said sleeve and extending above the upper end thereof, bars positioned between said sleeves and the upper ends 60 thereof terminating in a horizontal plane with the upper end of the first mentioned sleeve, bolts extending through the first mentioned sleeve and bars threaded to the inner sleeve, a sleeve surrounding the 65 upper end of the first mentioned sleeve and resting upon the second mentioned cap, an inner sleeve surrounding the upper end of the first mentioned inner sleeve, bars positioned between the sleeve resting upon the 70 second mentioned cap and the second mentioned inner sleeve, bolts extending through the sleeve resting upon the second mentioned cap and the second mentioned bars and threaded to the second mentioned inner 75 sleeve, and concrete within the shells and sleeves to form a continuous column.

In testimony whereof I affix my signature in presence of two witnesses.

JOSEPH PICURI.
